CLAIM

The ornamental design for control panel, as shown and described.

DESCRIPTION

FIG. 1 is a perspective view of a control panel showing our new design;

FIG. 2 is a top plan view thereof;

FIG. 3 is a front elevational view thereof;

FIG. 4 is a left end elevational view thereof;

FIG. 5 is a right end elevational view thereof; and
 FIG. 6 is a top plan view of a second embodiment thereof, the sides are identical to the first embodiment except for the lack of ornamental contour lines on the front and rear views.

The bottom plan views of both embodiments are flat and unornamented.

FIG. 1

FIG. 2

FIG. 3

FIG. 4

FIG. 5

FIG. 6
